ELECTRIC ACCUMULATOR

Eduard Willem Louis Ramakers, Bandoeng, Java,
Dutch East IndiesApplication November 11, 1935, Serial No. 49,294
In the Netherlands December 20, 1934

1 Claim. (Cl. 136—166)

The invention relates to an electric accumulator for the storage of electric energy, which may be used for example in motor cars and the like.

The well-known accumulators comprise cells the plates of which can only be removed with difficulty and with a considerable risk of damaging the pasted plates, making inspection and care of the interior impossible for those not skilled in the art and having no special equipment. With such storage batteries the deposit accumulating in the cells, and which may be considered the principal cause of interior short-circuits is difficult to remove, and flushing appears to be of little effect, in practice, for removing the impurities on the bottom and those between the plates.

Now the invention relates to an electric accumulator having a cover from which the plates are suspended, the plates being arranged in a jacket entirely or partly open at the bottom and constructed as an inner tank placed within an outer tank or vessel which holds the electrolyte. The accumulator is characterized by the fact that the walls of said inner tank near the upper parts are provided with outwardly protruding ribs forming, together with corresponding ribs of the inner wall of the outer tank and the upper parts of the walls of both tanks, a gutter-shaped space which may be filled up with a sealing material.

Further according to the invention inwardly protruding ribs can be arranged on the interior of the walls of the inner tank near the upper parts, the cover of the accumulator being supported by the said ribs, whereby the joint between them may be covered by sealing material.

This has for its effect that the inner tank can be removed in a simple way, without damaging the plates. The deposit can be removed without difficulty. The impurities and the flimsy insulation, if any, between the plates can be easily removed or interchanged. The condition of the plates can be examined. The above mentioned manipulations can even be carried out by unskilled people so that in comparison with the usual construction the duration of life is considerably increased by the simplicity with which the supervision and the cleaning can be effected, whereas the technical advantages can be attained without an increase of the manufacturing cost worth mentioning.

The invention will be elucidated by reference to an example shown in the drawing.

Fig. 1 is a fragmentary section on one corner of the accumulator showing how the various parts can be sealed up.

Fig. 2 is a side elevation of one of the cells of the accumulator, partly in section, and

Fig. 3 is an elevation of part of the accumulator, at right angles to Fig. 2, showing one of the cells partly in section.

In the drawing 3 is the inner tank composed, for example of a moldable insulating material, which in this case has perforated side walls, whereas the bottom side is open; this bottom, however, can also be constructed only partly open. If necessary the side walls could be provided with ventilation openings. The said inner tank houses a group of plates P and is supported upon ridges 4a on the bottom of an outer tank 4, with a free space between the side wall of the inner and outer tanks. The inner tank has integral handles 2 whereby it can be removed from the outer tank. Near the upper parts the walls of the inner tank and the outer tank are provided with ribs 6 (Fig. 1) which are directed towards each other and arranged on a level. After the fitting-up of the cell the said ribs will be in juxtaposition or in engagement. In that case both ribs 6 form the bottom of a gutter-shaped space the upright walls of which are formed by the upper parts of the walls of both tanks. The said gutter-shaped space may be filled up with a sealing-material such as bitumen, pitch or the like, or with a strip of rubber, in order to bring about a perfect closing.

Further the walls of the inner tank can also be provided with an inwardly protruding rib 7 receiving the edge of the cover 8. The edge which is formed in this manner may also be closed by a sealing-mass 5. It is also possible, however, to make the cover so that it forms one unit with the inner tank.

I claim:

In an electric accumulator, a group of plates, a cover from which said plates are suspended, a jacket surrounding said group of plates and at least partly open at the bottom, said cover being supported upon said jacket, an outer vessel surrounding said jacket, said jacket and vessel having ribs projecting, respectively, outward and inward just below their upper edges, and means in said outer vessel supporting said jacket so that its rib stands in non-overlapping relation at the same level with the rib on said vessel, to form a gutter bottom for receiving a sealing material.

EDUARD WILLEM LOUIS RAMAKERS.
